UNITED STATES PATENT OFFICE.

TIMOTHY STEBBINS, OF DAVENPORT, IOWA.

DESIGN FOR A CASING FOR FLOAT-VALVES.

SPECIFICATION forming part of Design No. 34,948, dated August 13, 1901.

Application filed April 1, 1901. Serial No. 53,960. Term of patent 14 years.

To all whom it may concern:

Be it known that I, TIMOTHY STEBBINS, a citizen of the United States, and a resident of Davenport, in the county of Scott and State of Iowa, have invented and produced a new and original Design for a Casing for Float-Valves, of which the following is a specification.

In the drawings, Figure 1 is a side view of a float-valve casing, showing my new design. Fig. 2 is a plan view of the valve-casing. Fig. 3 is a bottom view of the casing.

The principal feature of my new design is the short section of pipe A. This is substantially cylindrical throughout its entire length, excepting at its lower end a, where it is slightly increased in diameter and made po-

lygonal or nut-shape. The upper portion of this pipe is provided with a circumferentially-arranged series of openings b b therein. Projecting from the side of said pipe at its upper end is a lug D, the edge d of which farthest from the walls of said pipe is vertical, while the upper portion of its edge between said vertical portion and the pipe is rounded. 20 25

Having described my invention, what I claim as new, and desire to secure by Letters Patent, is—

The design for a casing for float-valves, as herein shown and described.

TIMOTHY STEBBINS.
